DESIGN FOR A COMBINED CHAIR AND VIBRATOR

John Werner, Chicago, and Albert H. Zeigler,
Kenilworth, Ill., assignors to Aciform Corpora-
tion, Chicago, Ill., a corporation of Illinois

Application November 12, 1947, Serial No. 142,473

Term of patent 7 years

(Cl. D15—1)

To all whom it may concern:

Be it known that we, John Werner and Albert H. Zeigler, both citizens of the United States of America, and residents of Chicago and Kenilworth in the county of Cook and State of Illinois respectively, have invented a new, original, and ornamental Design for a Combined Chair and Vibrator, of which the following is a specification, reference being had to the accompanying drawing, forming part thereof.

Figure 1 is a perspective view of a combined chair and vibrator, showing our new design.

Fig. 2 is a top plan view thereof.

Fig. 3 is a rear elevational view thereof.

Fig. 4 is a side elevational view thereof with the upper back panel shown broken away for convenience of illustration.

We claim:

The ornamental design for a combined chair and vibrator, as shown and described.

JOHN WERNER.

ALBERT H. ZEIGLER.
